ALLAN S. HUTCHINS, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

THREADING AND TENSION MECHANISM FOR LOOM SHUTTLES.

Application filed January 30, 1928, Serial No. 250,360. Renewed April 6, 1929.

This invention relates to improvements in automatic shuttles for weaving fine yarns such as silk or rayon, it being the general object of the invention to provide improved 5 tension and slack take-up devices in a self-threading shuttle.

In the weaving of very thin fabrics, such as silk, it is highly desirable that the tension of the filling or weft be maintained uniform. 10 Where some picks of filling are slack and others are tight, the resulting fabric is lacking in uniformity of appearance. Also in an automatic weft replenishing loom wherein the running shuttle is periodically supplied with a fresh supply of weft, it is essential 15 that the shuttle shall be self-threading in order that the weaving operation may be continuous.

It is, accordingly, an important object of 20 my invention to provide a shuttle which may be automatically threaded at the time of transfer and also capable of maintaining a uniform tension throughout the weaving operation, so that the finished cloth will have 25 a smooth appearance.

Shuttles for weaving silk are customarily provided with fur or similar material on one or both shuttle walls alongside the bobbin, in order to offer a certain resistance to the 30 unwinding of the weft and in order to prevent to a large extent any tendency of the yarn to uncoil from the end of the bobbin when the shuttle comes to rest. My improved 35 shuttle includes tension and take-up members which must be moved against yielding resistance during the shuttle threading operation, and in order that this resistance may be overcome, it is necessary for the fur or other friction material to offer a resistance 40 to the unwinding of the yarn which is somewhat greater than the resistance offered by the tensioning members. It is an important object of my present invention to provide a shuttle wherein the resistance offered by the 45 fur exceeds that offered by the tensioning members, so that the latter may be moved to effect threading.

It is a characteristic of artificial silk, such as rayon, that it lacks the inherent resilience

and elasticity which characterizes certain 50 other yarns. As a result, if a slight amount of yarn has been drawn off in excess of that actually required, when the shuttle comes to rest at the end of its flight, there will be no 55 tendency on the part of the yarn to take up the excess due to its inelastic qualities. A shuttle will also occasionally rebound after entering the shuttle box and a certain amount of yarn will be unwound and slackened by the slight rebound movement of the shuttle 60 toward the selvage.

It is an important part of my present invention to provide a slack taking-up device which will act on the occurrence of either of the conditions mentioned, keeping the filling 65 taut between the shuttle and the selvage when the shuttle is boxed, so that the proper tension may be preserved.

Certain kinds of silk yarn, such as that used in some crepes, is made with a very high 70 twist, the effect of which is to cause kinks or snarls whenever there is slackness in the yarn. This slackness may occur between the bobbin and the shuttle eye, with the result that a knot or kink is formed in the filling 75 which will cause breakage or undue strain when the shuttle is picked. A further object of my invention is to provide a take-up device which will operate to prevent the formation of these kinks.

Another object of my invention is to arrange the movable tension members with their threading portions between the bobbin and the pivots of said members, the weft in threading being drawn in a direction from 85 the pivots toward the bobbin. The amount of possible take-up increases as the weft is positioned more distantly from the pivots, due to the greater available movement of the inner or rearward ends of the tension members.

In the manufacture of weft yarn it is inevitable that breakages will occur, after which the ends of the yarn must be tied together. These knots, although small, will 90 nevertheless resist free passage through certain types of shuttle tension devices in use. It is a further object of my present inven-

tion to provide tensioning members so related to each other and to the weft yarn that the latter cannot be pinched between opposed surfaces but is caused to follow a tortuous path over smooth surfaces. Consequently, a knot present in the yarn will not be pinched between tensioning members but will be free to pass through a zigzag course over surfaces which will not impede its progress.

10 In weft replenishing looms, an essential result to be accomplished at the time of transfer is the disposal of the weft end which extends from the bobbin through the shuttle eye, between the shuttle and the shuttle binder, and back to the selvage, or to a cutting mechanism located along its path. When tension devices are employed which actually press the yarn between opposed surfaces, it is difficult for the yarn to slide freely through 15 the shuttle eye at the time the depleted bobbin is being expelled from the shuttle. By having the tension members so disposed as not to pinch the weft or to contact with each other, I provide means whereby the trailing 20 weft extending from the empty bobbin may be easily and quickly drawn through the shuttle eye at the time of transfer, with practically no resistance. I consider this an important feature of my invention in connection with the successful operation of automatic weft replenishing looms.

It is a more particular object of my present invention to provide a pair of oppositely moving tension members which are pivoted about 25 adjacent axes, located preferably below the lowest point which the weft is required to assume, the tension members having oppositely inclined portions which define an entrance notch for the weft located to one side of the 30 pivots of the members, and preferably above said pivots, so as to be more readily accessible to the weft. In connection with this feature of my invention, I provide the tension members with oppositely extending bearing portions 45 which may be sprung toward each other a sufficient amount to permit entry into their respective bearings.

I believe it to be broadly new and an outstanding feature of my invention to provide 50 a tension device in which separately and oppositely movable tension members act simultaneously to jointly tension the weft in a series of loops.

A specific feature of my invention relates 55 to the use of a single resilient element engaging both tension members and effective to move both of said members to their extreme or separated positions.

While the shuttle herein disclosed has been 60 described with special reference to a weft replenishing loom, the shuttle is also of more general utility as a self-threading shuttle, either in an automatic or a non-automatic loom.

65 My invention further relates to arrange-

ments and combinations of parts which will be hereinafter described and more particularly pointed out in the appended claims.

A preferred form of the invention is shown in the drawings in which

70 Fig. 1 is a plan view of a shuttle embodying my improvements;

Fig. 2 is an enlarged plan view of the threading end of the shuttle, partly in section;

Fig. 3 is a sectional side elevation, taken along the line 3—3 of Fig. 2;

Fig. 4 is a transverse sectional elevation, taken along the line 4—4 of Fig. 3;

Fig. 5 is a view similar to Fig. 3, but showing the parts in a different position; and

Fig. 6 is a partial side elevation of the shuttle, looking in the direction of the arrow 6 in Fig. 1.

Referring to the drawings, I have shown a shuttle comprising a body 10 having a bobbin 11 mounted therein and secured by the usual bobbin springs 12. Friction material 13 such as fur, may be provided to retard the unwinding of the weft from the bobbin. A recess or 85 thread passage 14 is provided at the front end of the shuttle and a rearwardly and downwardly extending delivery slot 15 (Fig. 6) is formed in the side wall of the shuttle and communicates with the recess 14. 90

95 My improved tension and take-up mechanism is mounted in the recess 14 and comprises a pair of tension members 16 and 18. The upper tension member 16 comprises an upper loop having side portions 20 and a closed end connection 22. Each side portion 20 has a downwardly and forwardly inclined leg portion 20^a, and a curved connecting part 100 providing a thread eye 24.

105 The lower tension member 18 similarly comprises an upwardly and forwardly extending loop having side portions 21 joined by an end portion 23. Forwardly extending leg portions 21^a are joined in continuous curves to the side portions 21, providing additional thread eyes 27.

110 At their lower ends, the leg portions 20^a and 21^a are bent outward to provide bearing or pivot portions 25. The portions 25 are centered in recesses in bearing blocks 26, 115 which are inserted tightly in pockets in the front and back side walls of the thread passage 14. The eye portions 24 and 27 alternate with each other transversely of the shuttle, as indicated in Figs. 2 and 4.

120 The tension members are resilient, so that the pivot or bearing ends 25 can be yieldingly drawn together when inserting the members in the shuttle, said bearing ends immediately springing apart when released, thus firmly retaining the tension members from displacement.

125 The tension members 16 and 18 are also provided with off-set portions 30 and 32 (Fig. 4) which are preferably engaged by the rear- 130

wardly extending ends of a single resilient member 33, shown herein as comprising a rubber band looped about a hook or projection 34 secured at the front end of the recess 14. The rear end portions of the band 33 extend through transverse holes in an adjusting screw 35 and are preferably knotted rearward of the holes as indicated in Fig. 3. The screw 35 has a close friction fit in the shuttle body and by turning the screw any desired tension may be placed upon the band 33.

It will be noted in Figs. 3 and 4 that the rearwardly extending portions of the band extend between the offset portions 30 and 32 and are displaced toward each other thereby, so that the band 33 continually tends to separate the tension members 16 and 18, moving them from the position shown in Fig. 5 to the position shown in Fig. 3.

As shown in Fig. 1, the top of the shuttle is provided with a plate P which lies in front of the thread passage 14 and partly covers the latter. The tension members 16 and 21 lie beneath this plate, as suggested in Fig. 1, being protected by the plate and also being properly located so that the plate may assist in directing the thread to the tension members.

The inclined portions 20^a and 21 of the associated tension members define an angular thread receiving notch N, shown clearly in Fig. 3, into which notch the thread T is directed by the portions 20^a and 21. The notch N being above the pivots of the tension members, the thread T may easily enter the notch without interference with the pivot portions.

The threading operation is extremely simple, the thread being drawn forward through the recess 14 on the first flight of the shuttle, and being guided rearward of the loom by the plate P to a position behind the tension members. The thread is then drawn sidewise or forward in the loom along the delivery slot 15 during the return flight of the shuttle, which latter movement causes the thread to pass into the notch N above the bearing blocks 26, the thread tension tending to cause relative separating movements of the tension members.

The friction material 13 in the bobbin serves to retard the unwinding of the weft during the threading operation, so that sufficient tension may be applied to the weft to move the overlapping tension members apart against the action of the resilient band 33.

As the movement of the thread continues, the members are moved against the tension of the band 33 past the position shown in Fig. 5 and the thread enters the narrow terminal portions or thread eyes 24 and 27 of the members 16 and 18. Any suitable slotted delivery eye may be provided at the lower end of the delivery slot.

When the loom is in operation, the shuttle is stopped very abruptly in the shuttle boxes

and the rapidly running thread has a tendency to continue to unwind, causing slackness and kinks between the end of the bobbin and the shuttle eye. Any rebound of the shuttle aggravates this condition. When such slackness occurs, the tension members 16 and 18 move apart, taking up a substantial amount of weft and effectively preventing the formation of kinks within the shuttle recess.

During the ejection of the depleted bobbin from the shuttle, the end of weft thread or filling extending from the bobbin may be easily drawn through the several parts of the tension device, as there is no pinching of the thread between the tension members. There is therefore very little chance that the shuttle will carry the weft end from the old bobbin into the warp shed.

It will be noted that the parts of the tension and take-up mechanism are exceedingly simple in construction, that they can be very readily assembled without the use of tools, that the tension thereon may be quickly and easily adjusted, and that replacement of the parts may be very easily made.

It is also found that the distribution of wear, caused by the relative angular movements of the tension members, greatly prolongs the period of service thereof.

Having thus described my invention and the advantages thereof, I do not wish to be limited to the details herein disclosed, otherwise than as set forth in the claim, but what I claim is:—

1. In a self-threading shuttle having a shuttle body with a forwardly extending threading recess formed therein and with a lateral weft delivery passage connected therewith, in combination, bearing blocks fixed in the side walls of said recess, and weft tension members pivoted in said bearing blocks and laterally compressible for removal therefrom.

2. In a self-threading shuttle having a shuttle body with a forwardly extending threading recess formed therein and with a lateral weft delivery passage connected therewith, in combination, a pair of tension members pivoted at the front of said recess and each having an offset portion adjacent its pivot, and resilient means engaging said offset portions to tension the weft engaged by said members.

3. In a self-threading shuttle having a shuttle body with a forwardly extending threading recess formed therein and with a lateral weft delivery passage connected therewith, in combination, a pair of tension members pivoted at the front of said recess and each having an offset portion adjacent its pivot, and a single resilient element engaging both of said offset portions and thereby tensioning the weft engaged by said members.

4. In a self-threading shuttle having a shuttle body with a forwardly extending threading recess formed therein and with a

lateral weft delivery passage connected therewith, in combination, a pair of tension members pivoted at the front of said recess and each having an offset portion adjacent its pivot, and a single resilient element having its end portions extending rearward between said offset portions, said end portions being displaced toward each other by said offset portions and exerting pressure to yieldingly 10 separate said tension members.

5. In a self-threading shuttle having a shuttle body with a forwardly extending threading recess formed therein and with a lateral weft delivery passage connected therewith, in combination, a pair of tension members pivoted at their forward ends in said recess and having overlapping weft engaging portions, a single resilient element engaging both of said tension members and thereby 15 tensioning the weft engaged by said members, and friction means in said shuttle effective to retard the delivery of weft to said tension members during the threading operation, whereby the weft may be drawn between said 20 tension members.

6. In a self-threading shuttle having a shuttle body with a forwardly extending thread passage formed therein and with a lateral weft-delivery passage connected therewith, in combination, a pair of weft-engaging 25 tension members pivoted at their forward ends in said shuttle and positioned adjacent the threading path of the weft, and means to yieldingly move said members apart to tension the weft, said members being normally in self-threading relation.

7. In a self-threading shuttle having a shuttle body with a forwardly extending threading recess formed therein and with a lateral weft delivery passage connected therewith, in combination, a pair of separately and oppositely movable tension members pivoted in said recess, and yielding means to move each of said members away from the other member to tension the weft engaged thereby 40 said members being normally in self-threading relation.

8. In a self-threading shuttle having a shuttle body with a forwardly extending threading recess formed therein and with a lateral weft delivery passage connected therewith, in combination, a pair of separately and oppositely movable tension members pivoted in said recess, and a single resilient element engaging both of said members and thereby 45 tensioning the weft engaged thereby said members being normally in self-threading relation.

9. In a self-threading shuttle having a shuttle body with a forwardly extending thread passage formed therein and with a lateral weft-delivery passage connected therewith, in combination, a pair of thread-engaging tension arms positioned in said 50 thread passage and pivoted at their forward

ends respectively in said shuttle, and means to yieldingly move said arms to tension the weft, each of said arms having a return portion, and said return portions overlapping in self-threading relation across the path of the 70 weft when said arms are in their normal position.

10. In a self-threading shuttle having a shuttle body with a forwardly extending thread passage formed therein and with a lateral weft-delivery passage connected therewith, in combination, a pair of thread-engaging tension arms pivoted at their forward ends in said shuttle, each of said arms having a return portion projecting forward 75 and above the path of the weft, and means to yieldingly move said arms to tension the weft.

11. In a self-threading shuttle having a shuttle body with a forwardly extending main thread passage formed therein and with a lateral weft-delivery passage connected thereto, in combination, a pair of tension members each mounted on spaced pivot bearings, one at the front and the other at the back of said main thread passage, and means to apply tension to the weft through movement of said members, said members having overlapping portions extending toward the longitudinal center of the shuttle and adapted to be engaged and moved apart 85 by the tensioning of the weft drawn therebetween during the self-threading of the shuttle.

12. In a self-threading shuttle having a shuttle body with a forwardly extending thread passage formed therein and with a lateral weft-delivery passage connected thereto, in combination, a pair of tension members each mounted to turn on horizontal pivots adjacent the threading path of the weft, and means to apply tension to the weft through movement of said members, said members having portions extending toward the longitudinal center of the shuttle adapted to be engaged and moved apart by the tensioning of the weft drawn therebetween during the self-threading of the shuttle and each member having interengaging portions limiting such longitudinal threading movement of the weft 100 relative thereto.

13. In a self-threading shuttle having a shuttle body with a forwardly extending thread passage formed therein and with a lateral weft-delivery passage connected therewith, in combination, a pair of thread-engaging tension members pivoted at their forward ends adjacent the threading path of the weft, means to yieldingly move said members to tension the weft, and means to guide the weft to the rear side of the weft-engaging portions of said tension members as said weft is initially inserted in said thread passage.

14. In a self-threading shuttle having a shuttle body with a forwardly extending 120

threading recess formed therein and with a lateral weft delivery passage connected therewith, in combination, a pair of movable tension members pivotally mounted at their forward ends in said recess and having overlapping weft-engaging portions, resilient means to move said tension members in opposite directions to tension the weft engaged thereby, and friction means in said shuttle effective to retard the delivery of weft to said tension members during the threading operation, whereby the weft may be drawn between said tension members.

15. In a self-threading weft-tensioning and slack take-up shuttle to operate with a wound mass of weft, a weft tensioning and slack take-up unit located at one end of the shuttle, said unit comprising a pair of coacting members, means defining a pivotal support for said members, said members having overlapping portions which extend in a direction from the pivotal support toward the wound mass of weft, yielding means in contact with the wound mass of weft effective to offer a relatively high resistance to the unwinding of the weft, and yielding means engaging said members and effective to offer a less resistance to separating movement of said members to permit entry of the weft therebetween, the weft during the threading of the shuttle moving along the members in a direction away from the pivotal support and towards the wound mass of weft, and the weft when in final normal position engaging those portions of the pivoted members which are most remote from the pivotal support.

16. In a self-threading weft tensioning and slack taking-up shuttle to be replenished by a full carrier of weft to be moved into the shuttle from one face thereof, a pair of relatively movable weft engaging, tension members having overlapping portions defining a notch, and pivotal supports for said members, said supports being so positioned that the notch is between the supports and that face of the shuttle from which a full weft carrier enters the shuttle.

17. In a self-threading shuttle having a shuttle body with a forwardly extending threading recess formed therein and with a lateral weft delivery passage connected therewith, in combination, a pair of separately and oppositely movable tension members pivoted in said recess at opposite sides thereof, and yielding means to move both of said members to tension the weft engaged thereby said members being laterally compressible for removal from said shuttle.

18. In a self-threading shuttle having a shuttle body with a forwardly extending thread passage formed therein and with a lateral weft-delivery passage connected therewith, in combination, a pair of weft-engaging tension members pivoted at their forward ends in the opposite side walls of said shuttle below the threading path of the weft and positioned adjacent the threading path of the weft, and means to yieldingly move said members apart to tension the weft.

In testimony whereof I have hereunto affixed my signature.

ALLAN S. HUTCHINS.
